FEELER MECHANISM FOR LOOMS

Application filed January 28, 1929. Serial No. 335,717.

This invention relates to feeler mechanism for looms and more particularly to feeler mechanisms of the side slipping type wherein by side slipping movement of the feeler upon 5 the occurrence of substantial exhaustion of filling a change is effected in the loom operation, such, for instance, as filling replenishment.

In feeler mechanisms of the side slipping 10 type the feeler is given its side slipping movement on substantial exhaustion of filling; either by frontward pressure upon the feeler or by mechanical means, such, for instance, as a spring. In such feeler mechanisms there is a constantly increasing tendency to impart to the feeler its side slipping movement as the lay advances in the beat-up and this tendency is augmented when the feeler itself holds a working supply of 15 filling in the shuttle on a detecting beat, with the result that at times filling replenishment may be called even though a working supply of filling is present in the shuttle. As the filling is gradually withdrawn from the 20 shuttle the tendency for side slipping movement gradually decreases until, when the filling is substantially exhausted, this tendency is at a minimum. This variation in 25 tendency for side slipping movement of the 30 feeler as above outlined is just the opposite of what is desired in the ideal feeler mechanism.

Should the feeler call for a change of filling due to the increased stress upon the feeler 35 exerted by a working supply of filling in the shuttle on a detecting beat much waste of yarn or filling would result.

One of the important features of the present invention is to provide a side slipping 40 feeler mechanism for looms in which the feeler may be prevented from side slipping movement when a working supply of filling is present in the shuttle and be permitted to partake of such movement only when the 45 filling has become nearly or substantially exhausted.

The invention and novel features thereof will best be made clear from the following 50 description and the accompanying drawings of one good practical form thereof.

In the drawings:

Fig. 1 is a perspective view of a feeler mechanism containing the present invention;

Fig. 2 is a plan view showing the relation of parts when the feeler is moved frontwardly by a working supply of filling in the shuttle; and

Fig. 3 is a similar plan view showing the relation of parts when the feeler detects substantial exhaustion of filling in the shuttle.

The feeler mechanism of the present invention is associated with means for changing the loom operation when the feeler side slips on a detecting beat, and more particularly to effect replenishment of filling in the shuttle 60 at such times, but since the filling replenishing mechanism may be of any usual construction and its details form no part of the present invention it is not necessary herein to illustrate it and describe it.

The loom frame may be of any usual construction and have extending therefrom the shipper stand 1 from which projects the supporting arm 2 to which the feeler mechanism of the present invention may be secured. 70 In the present instance the feeler stand 3 may be secured to the part 2 by means of a bolt 4, but, obviously, the manner of securing the feeler in place may be varied. The feeler stand 3 may preferably rest upon a bracket 5 75 and be secured in adjustable position thereon by means of a bolt 6 extending through a slot 7 formed in the feeler stand, and in this case the bracket 5 will be secured to the loom frame by the bolt 4, as usual in this type of mechanism.

The feeler stand 3 is herein shown as formed of a plate the rear end portion of which has an upwardly extending flange 8 provided with an opening 9 through which the feeler 10 extends, and the opening 9 is of such dimension as to permit the feeler to have both movement towards and from the front of the loom and also in a direction longitudinally of the shuttle.

The feeler 10 is preferably formed as a wire of sufficient rigidity, although, of course, its construction may be varied in this particular, and as shown, the rear end portion of the feeler 10, that is, the part which con-

stitutes the filling feeling end, is shown as slightly beveled at 11, but so far as the features of the present invention are concerned the end of the feeler may be modified in accordance with the usual practice of today. 5 Mounted on the feeler stand 3 is the fulcrum stop 12 against which the rearwardly extending portion of the feeler bears and about which the feeler turns as a fulcrum when it 10 partakes of its side slipping movement.

In accordance with the present invention, the feeler has an extension or arm projecting frontwardly of the fulcrum stop 12, and where the feeler is formed of wire-like material, as shown, the said projection or arm may be formed by extending the body of the feeler frontwardly and turning it or bending it, as at 13, and in order to limit the rearward movement of the feeler into its feeling position 15 the main body portion of the feeler is provided with a projection 14 which may also, if desired, be constituted as a bend in the body of the feeler material. The projection or arm leads frontwardly from the fulcrum stop 20 and is carried rearwardly from the bend 13, as at 15, and its rear end portion 16 is connected to one end of a spring 17, the other end of which is connected at 18 to a support 19* so that the stress of the spring is exerted 25 upon the feeler in a rearward and lateral direction on a line passing back of the fulcrum stop 12 when the feeler is in its rearward feeling position, so that the action of the spring 17 not only moves the feeler to its 30 feeling position but when in feeling position 35 stresses the feeler to hold it in the position indicated in Fig. 1.

When the feeler is moved frontwardly on a detecting beat, the spring connection at 16 40 is carried frontward of the fulcrum stop 12, as indicated in Figs. 2 and 3, and thereupon the spring exerts a stress upon the feeler tending to impart to the feeler its side slipping movement.

45 Ordinarily the filling engaging end portion of the feeler will be held by the filling on a detecting beat so that the feeler will not side swipe, and this is usually characteristic of side slipping feelers. However, since the 50 tendency of the spring to cause side slipping movement of the feeler increases progressively as the lay moves frontwardly on a detecting beat, and since, when a working supply of filling is present in the shuttle, this tendency to side swipe movement of the feeler is 55 proportionately increased, the present invention provides that when the feeler is moved frontwardly by a working supply of filling in the shuttle on a detecting beat that the increased 60 tendency of the spring to impart side slipping movement to the feeler will be prevented from effecting such movement, thereby preventing a call for change of filling when a working supply still remains in the 65 shuttle. To effect this prevention of side

slipping movement of the feeler under the conditions stated, a feeler side slipping stop is employed which is engaged by the feeler when the latter is moved frontwardly by a working supply of filling in the shuttle. 70

In the present instance of the invention, the feeler side slipping stop is supported upon the feeler stand frontward of the end or bent portion 13 of the feeler and, as shown, is constituted by an arm 18 secured to the feeler stand by a bolt 19 or similar means and where the feeler side slipping stop is formed of light material, such as wire, in the present instance, the end portion 20 thereof is carried laterally from the bolt 19 and has connected thereto a light spring 21, the opposite end of which is connected to a pin 22, and to prevent undue movement of the feeler side slipping stop a pin 23 is conveniently employed against which the arm 18 of the feeler may bear under 75 the light stress of the spring 21.

Extending rearwardly from the arm 18 is the feeler side slipping stop proper, designated as 24, and where the stop is formed of material such as wire it may be bent at the connection with the arm 18, as shown. Of course the feeler side slipping stop may be variously contrived but the form shown constitutes a good practical embodiment of this feature of the invention, and the rear end portion of the stop 24 may be appropriately beveled, as at 25, so that in case the frontwardly extending portion of the feeler should contact with the end of the stop as the feeler moves frontwardly, it will slide off the end of the stop and not cause breakage or distortion of any of the parts. Injury of the feeler side slipping stop by the forward movement of the feeler in a direction to cause the feeler end 13 to strike against the end 25 of the stop 24 100 is further prevented by the yielding pivotal mounting of the arm 18 and stop 24, whereby the latter may yield frontwardly in case its end 25 is struck by the forwardly moving feeler. 105

As more clearly indicated in Fig. 2, the limit of rearward movement of the feeler under the action of the rearwardly and laterally inclined spring 17 may be effected by the bent portion or shoulder 14 formed on the main part of the feeler, the construction being such that when the feeler is in its rearward feeling position the stress of the spring 17 will not only hold it in its rearward feeling position but act in a direction back of the fulcrum stop, as indicated in Fig. 1, to maintain the feeler in its proper backward position with the main body of the feeler resting against the wall at one end of the opening 9, as indicated in Fig. 1. 110

As usual in side slipping feeler mechanisms for looms, the side slipping action of the feeler is utilized through a train of mechanism to effect replenishment of filling, and in the present instance of the invention the 115 120 125

feeler stand is provided with a perforated lug 26 through which extends the transmitter 27, the end 28 of which rests in the path of the feeler as it side slips, so that the transmitter 5 will be moved to effect replenishment of filling.

Only a small portion of the lay 29 is shown as provided with the usual shuttle box 30 in which the shuttle 31 may rest on the detecting beat of the lay. The front wall of the shuttle box and the front wall 32 of the shuttle may be appropriately provided with openings, such as 33, as usual in this class of looms, for the entrance of the feeler on a detecting beat. 10 As usual, also, the shuttle has mounted there-in the filling carrier or bobbin 34 by means of the usual bobbin holding springs 35, and on the bobbin 34 the filling 36 is wound.

During the loom operation with a working supply of filling in the shuttle, as indicated in Figs. 1 and 2, the feeler will be moved frontwardly and the spring 17 will exert a constantly increasing tendency to move the feeler longitudinally of the shuttle or cause it 20 to side slip, and when the stress of the spring 17 is approaching its maximum, the frontwardly extending arm of the feeler will engage at the side of the feeler side slipping stop 24, with the result that during the maximum tendency of the spring to cause side slipping movement of the feeler, the latter will be positively prevented from side slipping and calling a change when a working supply 30 of filling is in the shuttle. As the filling is withdrawn from the shuttle during weaving, that portion thereof which is engaged by the feeler will gradually become less and less in diameter until, when the filling is substantially exhausted, as indicated in Fig. 3, the frontwardly extending feeler arm will not be moved frontwardly sufficiently far to engage the feeler side slipping stop, with the result that the feeler will side slip and call for replenishment of filling.

The invention described as a good practical form thereof thus effectively prevents a change of filling and consequent waste when the shuttle contains a working supply of filling, because the frontwardly extending arm 45 portion of the feeler engages the feeler side slipping stop and regardless of the tendency of the feeler to side slip, such movement will be prevented. When, however, the filling 50 has become substantially exhausted, the feeler will not be moved frontwardly far enough to cause its frontwardly extending arm to engage the feeler side slipping stop, as indicated in Fig. 2, and the feeler will thereupon side slip and effect replenishment of filling.

During the movement of the feeler towards and from the front of the loom it will bear upon the fulcrum stop 12 and when the feeler 55 side slips it will partake of such movement

about the fulcrum stop as a center, as indicated in Figs. 2 and 3.

What is claimed is:

1. In a feeler mechanism for looms, the combination of a feeler stand, a side slipping feeler mounted on the feeler stand, a fulcrum stop for the feeler, an arm extending frontwardly from the feeler beyond the fulcrum stop, a spring acting laterally and rearwardly upon the feeler rearward of the fulcrum stop when the feeler is in rearward feeling position and frontward of the fulcrum stop when the feeler is moved frontwardly to then impart a tendency for the feeler to side slip, and a stop positioned to cooperate with said arm for preventing side slipping movement of the feeler when it is moved frontwardly a predetermined distance from its feeling position. 70

2. In a feeler mechanism for looms, the combination of a feeler stand, a side slipping feeler mounted on the feeler stand, a spring acting upon the feeler with a tendency to move the feeler longitudinally of the shuttle on a detecting beat, a feeler side slipping stop engaged by the feeler when it is moved frontwardly a predetermined distance by a working supply of filling in the shuttle to prevent side slipping movement of the feeler, and means for supporting said stop for movement out of the path of the feeler when it is struck by the forwardly moving feeler. 80

3. In a feeler mechanism for looms, the combination of a feeler stand, a feeler mounted directly on the feeler stand for side slipping movement, a fulcrum stop against which the feeler bears and turns, a spring connected to the feeler and acting on the feeler in a rearwardly inclined direction back of the fulcrum stop when the feeler is in rearward feeling position and frontward of the fulcrum stop when the feeler is moved frontwardly on a detecting beat to thereby exert a tendency for the feeler to side slip, and a feeler side slipping stop positioned to be engaged by the front end portion of the feeler to prevent side slipping movement of the feeler as it is moved frontwardly by a working supply of filling in the shuttle. 95

4. In a feeler mechanism for looms, the combination of a feeler mounted for movement towards and from the front of the loom and in a direction longitudinally of the shuttle, a feeler side slipping stop which is engaged by the feeler in case it is moved frontwardly by a working supply of filling in the shuttle on a detecting beat to prevent side slipping movement of the feeler while a working supply of filling is in the shuttle, and means for supporting said stop or swinging movement out of the path of the feeler when it is struck by the forwardly moving feeler. 100

5. In a feeler mechanism for looms, the combination of a feeler mounted for move- 115

ment towards and from the front of the loom and in a direction longitudinally of the shuttle, a fulcrum stop against which the feeler bears and turns, and a feeler side slipping stop mounted frontwardly of the fulcrum stop in position to be engaged by the feeler in case it is moved frontwardly by a working supply of filling in the shuttle on a detecting beat to prevent side slipping movement of the feeler while a working supply of filling is in the shuttle.

6. In a feeler mechanism for looms, the combination of a feeler mounted for movement towards and from the front of the loom and in a direction longitudinally of the shuttle, a feeler side slipping stop which is engaged by the feeler in case it is moved frontwardly by a working supply of filling in the shuttle on a detecting beat to prevent side slipping movement of the feeler while a working supply of filling is in the shuttle, and means for supporting said stop so that it may yield sufficiently to prevent injury by the forward movement of the feeler.

7. In a feeler mechanism for looms, the combination of a feeler mounted for movement toward and from the front of the loom and in a direction longitudinally of the shuttle, a fulcrum stop about which the feeler turns when it side slips, an arm on the feeler extending frontward of the fulcrum stop, and a feeler side slipping stop adapted to be engaged by the feeler arm to prevent side slipping movement of the feeler when it is moved frontwardly by a working supply of filling on a detecting beat.

8. In a feeler mechanism of the side slipping type, a feeler having a single point filling engaging end and mounted for side slipping movement, a fulcrum stop, an arm on the feeler extending frontward of the fulcrum stop, a feeler side slipping stop which is engaged by the feeler arm only when the feeler is moved frontwardly by a working supply of filling on a detecting beat that the feeler may partake of its side slipping movement when the filling is substantially exhausted on a detecting beat and be prevented from side slipping movement when the feeler is moved frontwardly by a working supply of filling.

In testimony whereof, I have signed my name to this specification.

JESSE W. SIMPSON.
